CALENDAR

Jacob Brenner, Maplewood, N. J.

Application March 31, 1933. Serial No. 663,689

6 Claims. (Cl. 40—109)

This invention relates to a perpetual calendar that can be made of different sorts of material that have some rigidity and are capable of receiving writing or printing thereon, such as thick 5 paper, cardboard, etc.

In carrying out this invention a sheet is perforated or provided with openings through which the month, as well as the days can be observed for three months in succession and the calendar 10 can be changed from month to month indefinitely. A disc is provided upon which the names of the twelve months may be placed and sliding strips are also provided containing the names of months, the days of the week and the days in 15 the month.

The invention will be understood from the description in connection with the accompanying drawing in which Fig. 1 is a front view of the device; Fig. 2 is a view from the back side thereof and Figs. 3, 4 and 5 are plan views of some of the details.

In the drawing reference character 1 indicates a sheet of paper or other material that may be ornamented in any appropriate way. This sheet 25 is provided with rectangular openings 2, 3, 4, 5, 6 and 7 through which insignia relating to a calendar can be observed. A row of letters is applied to the sheet 1 above the openings 7 to indicate days of the week. A chart A is applied to the sheet 1 to the right of the opening 2 with the numerals arranged in groups of seven to indicate days of the month, and a similar chart B is applied to the right of the opening 4.

A second sheet 8 of paper or other material 35 is attached to the back side of the sheet 1 in any convenient manner, as by cloth hinges or by gluing the edges of the sheet 8 to the back of the sheet 1, for example.

A strip 9 (Figs. 2 and 4) is provided with the 40 names of the months beginning near the center and extending for half the months in one direction and then beginning near the center and extending for the other months in the other direction so that this strip can be moved in front 45 of the opening 3 and reversed in position. In this way more room is provided for increased sizes of lettering thereon than would be the case if this strip had to be moved in one direction through the space occupied by the twelve months. The strip 9 is inserted through slots 10 and 10' in the sheet 8 so that the desired month 50 on the face thereof will be visible through the opening 3 in the sheet 1. The strip 9 is reversed when the months on one half have been passed. 55 A strip 11 like the strip 9 is inserted through

slots 12 and 12' in the sheet 8 so that the names of the months thereon will be visible through the opening 5.

A strip 13 (Figs. 2 and 3) that is narrower than the strip 9 bears on one side the names (or initials) of the days of the week. Two sets of these initials in a single row are preferably provided. The strip 13 passes through slots 14 and 14' in the sheet 1 in position so that the week days are visible through the opening 2 in the sheet 1.

A strip 15 like the strip 13 passes through slots 16 and 16' in the sheet 8 so that the days of the week on it are visible through the opening 4 in the sheet 1. A disc 17 is revolvably mounted at 70 its center 18 upon the sheet 8 so as to lie between the sheets 8 and 1. The upper edge of the disc 17 objects above the sheet 8 so that this disc is readily accessible in order that it can be turned by the fingers of the user. 75

Spaced slits 19 and 20 are provided in the sheet 8 and a horizontal slit 21 connects the slits 19 and 20 near their middle, thus providing a flap 22. The sheet 8 is cut out and discarded between the slit 21 and a slit 23 joining the ends of the slits 19 and 20, thus exposing the lower edge of the disc 17. A strip 24 (Figs. 2 and 5) which is wider than the strip 9 is inserted through the slits 19 and 20 in the sheet 8 and its upper edge extends beneath the lower edge of the disc 17 so that the disc 17 aids in keeping the strip 24 in place. The strip 24 is provided with numerals indicating days of the month, as shown in Fig. 5.

The operation is as follows: 90

The disc 17 is turned until the current month and the days in the month are visible through the opening 6. The strip 24 is slid until the numeral 1 thereon is immediately below the letter, which indicates the day upon which the month begins. This letter is one of the series of letters on the sheet 1 above the opening 7 which indicate the days of the week. 95

When the month expires the disc 17 is turned until the next month is visible through the opening 6 and the strip 24 is moved to the appropriate place. 100

The strip 9 is moved so that the month preceding the one visible through the opening 6 is visible through the opening 3, and the strip 12 is moved until the month succeeding the month visible through the opening 6 is visible through the opening 5. Also, the strip 13 is moved to the position where the day upon which the month visible through the opening 3 begins is in 110

line with the row of numerals 1, 8, 15, 22 and 29 on the chart A, and the strip 15 is moved to the position where the day of the week upon which the month visible through the opening 5 begins is in line with the same row of numerals 5 on the chart B. In this position of the parts one can read the calendar for three successive months and the calendar can be adjusted for any other three months for any year.

10. I claim:

1. A calendar comprising a sheet with openings therein, a second sheet attached to said first named sheet, a disc bearing the names of months revolubly mounted on one of said sheets, 15 said second named sheet having slits therein, and strips, one of which bears the names of days of the week and the other bears the names of months, in said slits slideable along said openings.
2. A calendar comprising a sheet with openings therein, a second sheet attached to said first named sheet, a disc bearing the name of months revolubly mounted on one of said sheets, 20 said second named sheet having slits therein, and a strip for days of the week slideable in some of said slits along one of said openings.
3. A calendar comprising a sheet with openings therein, a second sheet attached to said first named sheet, a disc bearing the names of months revolubly mounted on one of said sheets, 25 said second named sheet having slits

therein, and a strip for months of the year slideable in some of said slits along one of said openings.

4. A calendar comprising a sheet with openings therein, a second sheet attached to said first named sheet, a disc bearing the names of months revolubly mounted on one of said sheets, 80 said second named sheet having slits therein, and a strip for days of the month slideable in some of said slits along one of said openings.

5. A calendar comprising a sheet with openings therein, a second sheet attached to said first named sheet, a disc bearing the names of months revolubly mounted on one of said sheets, 85 said second named sheet having slits therein, and a strip for days of the month slideable in some of said slits along one of said openings.

90

6. A calendar comprising a sheet with openings therein, a second sheet attached to said first named sheet, a disc bearing the names of months revolubly mounted on one of said sheets, 95 said second named sheet having slits therein, and strips in said slits slideable along said openings, one of said strips having thereon names of the months in two series extending in opposite directions and lying on opposite sides of its center line.
